UNITED STATES PATENT OFFICE.

WILLIAM HAWKS, OF DULUTH, MINNESOTA, ASSIGNOR OF ONE-HALF TO CHARLES W. ANDREWS, OF DULUTH, MINNESOTA.

WATER-HEATING APPARATUS.

1,054,202.

Specification of Letters Patent. Patented Feb. 25, 1913.

Application filed October 22, 1909. Serial No. 523,946.

To all whom it may concern:

Be it known that I, WILLIAM HAWKS, a citizen of the United States, residing at Duluth, in the county of St. Louis and State of Minnesota, have invented certain new and useful Improvements in Water-Heating Apparatus, of which the following is a specification.

This invention relates to improvements in water heating apparatus more particularly adapted for use with domestic stand boilers and the primary object of the invention is to provide an improved form of heater which may be readily attached to the bottom of an ordinary stand boiler without changing the construction of the boiler and in which the water will enter the heater from the boiler and be discharged from the heater back into the boiler through a single opening in the bottom of the boiler.

A further object is to provide an improved device of this character in which the water will enter the heater at a point lower than the discharge outlet of the heater to induce circulation.

A further object is to provide an improved form of connection between the heater and the boiler.

A further object is to provide an improved device of this character which will be simple, durable and cheap in construction and effective and efficient in operation.

To the attainment of these ends and the accomplishment of other new and useful objects, as will appear, the invention consists in the features of novelty in the construction, combination and arrangement of the several parts hereinafter more fully described and claimed and shown in the accompanying drawing, illustrating an embodiment of the invention, and in which—

Figure 1 is a longitudinal sectional view of an improved device of this character constructed in accordance with the principles of this invention, showing the same attached to a boiler and showing a portion of the boiler in section. Fig. 2 is a detail sectional view on line 2—2 of Fig. 1. Fig. 3 is a detail sectional view on line 3—3 of Fig. 1. Fig. 4 is a view similar to Fig. 1 of a modified form of the invention.

Referring more particularly to the drawing and in the present exemplification of the invention, the numeral 10 designates a portion of the ordinary domestic stand boiler,

which is provided with a supply inlet pipe 11, which preferably extends from the top of the boiler to a point adjacent the bottom thereof. This boiler is provided with the usual outlet (not shown).

The bottom 12 of the boiler is provided with an opening preferably located at the center thereof and extending through this opening is a tubular member designated generally by the reference numeral 14. This tubular member is provided with peripheral screw threads 15 intermediate its ends which are adapted to engage corresponding screw threads in a suitable collar 16 which surrounds the opening in the bottom of the boiler, to form a support for the tubular member. The tubular member 14 is provided with a partition 17 extending longitudinally thereof to form two passages 18, 19. One of the passages 19 opens through the side of the tubular member 14, adjacent one end as at 20 and the other passage 18 extends directly through the ends of the tubular member. A portion of one end of the tubular member is cut away so that the end of the partition 17 will project below the end of the passage 18, as at 21. The tubular member is connected to the bottom of the boiler 12 so that one end thereof will project into the boiler a sufficient distance to permit the opening 20 of the passage 19 to have communication with the boiler 10. The other end of the tubular member depends below the boiler, and connected thereto and preferably spaced a short distance from the bottom of the boiler, is a water heater 22 which is provided with an annular chamber 23 and a chamber 24, which latter is preferably located at the diametric center of the heater. The annular chamber 23 has communication with the chamber 24 by means of a passage 25 which forms an outlet from the chamber 24 to the chamber 23. The chamber 23 also has communication with the chamber 24 by means of an upwardly inclined passage 26, the outlet end 27 of which passage is located above the bottom of the passage 25.

The water heater 22 is secured to and supported by the tubular member 14 preferably by means of a screw threaded connection 28 between the extremity of the tubular member 14 and the top of the water heater. The portion 21 of the partition and the coöperating portion of the wall of the tubular

member which extends below the cut off extremity of the tubular member, projects into the chamber 24 of the water heater, and terminates at a point in proximity to the bottom of the chamber. The passage 18 in the tubular member also has communication with the chamber 24 above the point of communication between the passage 19 and the chamber 24.

Secured to the extremity of the tubular member 14 which is located within the boiler 10 is a tubular member 29, which extends to a point above the discharge extremity of the tubular member 11 so that the water being discharged from the chamber 24 will enter the boiler 10 at a point above the discharge outlet of the supply pipe 11.

The water heater is provided with a reinforced portion 30, preferably arranged at the center thereof, with which portion one extremity of the support 31 has engagement and which support also rests upon the floor or ground.

With this improved construction it will be apparent that the heater will be supported directly by the standard 31 and the boiler will be supported by the heater through the medium of the tubular member 14 and by the provision of the single tubular member having a plurality of passages therein, to form an inlet to the heater from the boiler and an outlet from the heater to the boiler, it is necessary to provide only a single opening and a single connection between the bottom of the boiler and the heater, thereby not only reducing the expense of installation but also rendering it possible to attach this improved heater to an old boiler or a boiler of the ordinary construction, without providing any additional openings in the bottom of the boiler for the circulation pipes.

The burner 32 is adjustably supported on the standard 31 below the heater whereby the distance between the burner and the heater may be varied to meet the existing conditions and the flange 33 depends from the heater and surrounds the burner to direct the flame against the bottom of the heater.

It will be apparent that the water will flow from the boiler into the passage 19 of the tubular member through the opening 55 20 which is located in close proximity to the bottom of the boiler and will be discharged into the heater adjacent the bottom of the chamber 24 from which chamber the water will pass through the passage 25 into the annular chamber 23 and from the annular chamber 23 back into the chamber 24 through the upwardly inclined passage 26 and back into the boiler from the chamber 24 through the passage 18 of the tubular member 14 and the tubular member or pipe

29. With this arrangement it will be noted that the water enters the annular chamber 23 at a point below the discharge outlet from said chamber so that a circulation will be induced in the heater.

In the exemplification shown in Fig. 4 the water heater 34, which corresponds to the water heater 22 in Figs. 1 and 2, is provided with a tubular extension designated generally by the reference numeral 35, which is supported within and spaced from the annular heating chamber 23, is formed integral therewith and extends above the heating means and at the diametric center thereof. This tubular extension 35 preferably decreases in diameter from the bottom to the upper extremity and is provided with a partition 36 to form two passages 37, 38, therethrough. The tubular member includes the receptacle 39, and the partition 36 extends into the receptacle 39 and to the bottom thereof. The upper end 40 of the tubular member 35 is provided with peripheral screw threads 41 similar to the threads 15 on the tubular member 14 and a collar 42 is secured to the bottom 43 of the boiler 44 to surround an opening in the bottom of the boiler through which the extremity 40 passes. The peripheral threads 41 on the tubular member 35 are adapted to engage the threads in the collar 42. The passage 37 opens through the side of the tubular member as at 45 adjacent the extremity 40 and above the bottom 43 of the boiler while the passage 38 opens through the end of the tubular member and to which end a pipe 46 is connected for discharging the water into the boiler.

The passage 47 in the water heater 34 corresponds with the passage 25 in the water heater 22 and is adapted to receive the water from the passage 37 which enters the latter passage from the boiler 44 through the opening 45. The water entering the passage 47 will be discharged into the annular chamber or passage 48, which corresponds to the annular heating chamber 23 in Figs. 1 and 2, and will be discharged therefrom into the passage 49 which corresponds with the passage 26 of the heater 22. From the passage 49 the water will enter the receptacle 39 on the other side of the partition 36 to flow through the passage 38 and discharge into the boiler 44 through the tubular member or pipe 46. In this exemplification of the invention, the water will be discharged into the water heater at a lower point than the discharge outlet from the heater, thereby inducing circulation of the water through the heater.

If desired, instead of providing a jacket 50, which is supported by the water heater and which surrounds the boiler and is spaced therefrom so as to form a passage for the products of combustion from the

burner around the boiler, this jacket may be dispensed with and a cap or flanged member 51, shown in dotted lines in Figs. 1 and 4, may be provided, which is supported preferably by the bottom of the boiler to prevent the products of combustion from the burner from rising above the bottom of the boiler.

In order that the invention might be fully 10 understood the details of the foregoing embodiment thereof have been thus specifically described, but

What is claimed as new is—

1. In a water heating apparatus the combination of a water container, an annular heating chamber, a tubular member supported within and spaced from said annular heating chamber to admit of the passage of heated air between said annular heating 20 chamber and said tubular member, said tubular member having an inlet duct adapted to receive water from said container and discharge it into and adjacent the lower extremity of said annular chamber and having a separate outlet duct adapted to receive water from said annular chamber at a point remote from the lower extremity thereof and discharge it into said container, said annular heating chamber having a horizontal circulating passage communicating with said inlet duct, an upwardly inclined circulating passage communicating with said outlet duct, and means for heating said annular heating chamber and said tubular member.

25

2. In a water heating apparatus the combination of a water container, an annular heating chamber, a tubular member supported within integral with and spaced from said annular heating chamber to admit of the passage of heated air between said annular heating chamber and said tubular member, said tubular member having an inlet duct adapted to receive water from said container and discharge it into and 30 adjacent the lower extremity of said annular chamber and having a separate outlet duct adapted to receive water from said annular chamber at a point remote from the lower extremity thereof and discharge it into said container, said annular heating chamber having a horizontal circulating passage communicating with said inlet duct, an upwardly inclined circulating passage 35 communicating with said outlet duct, and means for heating said annular heating chamber and said tubular member.

30

said annular heating chamber and said tubular member.

2. In a water heating apparatus the combination of a water container, an annular heating chamber, a tubular member supported within integral with and spaced from said annular heating chamber to admit of the passage of heated air between said annular heating chamber and said tubular member, said tubular member having an inlet duct adapted to receive water from said container and discharge it into and 40 adjacent the lower extremity of said annular chamber and having a separate outlet duct adapted to receive water from said annular chamber at a point remote from the lower extremity thereof and discharge it into said container, said annular heating chamber having a horizontal circulating passage communicating with said inlet duct, an upwardly inclined circulating passage 45 communicating with said outlet duct, and means for heating said annular heating chamber and said tubular member.

In testimony whereof I have signed my name to this specification in the presence of two subscribing witnesses, on this 26th 50 day of June A. D. 1909.

WILLIAM HAWKS.
